UNITED STATES PATENT OFFICE.

EARL E. MCCOLLUM, OF DOWNTERS GROVE, ILLINOIS.

VALVE.

1,179,120.

Specification of Letters Patent. Patented Apr. 11, 1916.

Original application filed April 5, 1915, Serial No. 19,285. Divided and this application filed July 21, 1915.
Serial No. 41,054.

To all whom it may concern:

Be it known that I, EARL E. MCCOLLUM, a citizen of the United States, residing at Downers Grove, in the county of Dupage 5 and State of Illinois, have invented certain new and useful Improvements in Valves, of which the following is a specification.

My invention relates to improvements in valves and more particularly to valves for internal combustion engines.

A particular object of my invention is to provide a rotary valve, such as will automatically care for any wear that may be occasioned by continued usage.

Another object of my invention is to provide such a rotary valve as will be practically equalized under varying temperatures so as to prevent seizure or difficulties in lubrication due to unequal expansion.

Another object of my invention is to provide a valve particularly adapted for association with a valve operating means illustrated and described in my copending application Serially Numbered 19,285 entitled 25 Valve and valve motion, filed April 5th, 1915, of which the present application is a division.

Other and further objects of my invention will become readily apparent to persons skilled in the art, from a consideration of the following description when taken in conjunction with the drawings, wherein:

Figure 1 is a vertical, central section of an engine provided with one embodiment of my invention. Fig. 2 is a fragmentary section taken on line 2—2 of Fig. 1. Fig. 3 is a section taken on line 3—3 of Fig. 1. Fig. 4 is a central vertical section of the valve, valve casing and means for rotating the 40 valve showing the intake port closed by the valve. Fig. 5 is a transverse section taken on line 5—5 of Fig. 4. Fig. 6 is a transverse section taken on line 6—6 of Fig. 4. Fig. 7 is an elevation, part in section, of an internally toothed, valve-moving sleeve, for rotating the valve. Fig. 8 is a transverse section, taken on line 8—8 of Fig. 4. Fig. 9 is a view similar to Fig. 4 showing the intake port open. Fig. 10 is a perspective view of 50 the valve.

In all the views the same reference characters are employed to indicate similar parts.

I have shown my invention in connection

with an internal combustion engine of the usual type, wherein 15 is the crank casing, 16 is the crank, 17 the wrist pin, 18, the main driving shaft, 19 the cylinder, 20 the reciprocating piston therein, and 21 the pin by which the connecting rod 22 is connected to the piston. The other end of the connecting rod being connected to the wrist pin, as at 23. 24 is a water jacket around the combustion chamber 25. These features are typical of engines of this character.

The cylinder head 26 is perforated, as at 27, and to the upper end of the cylinder is connected a valve casing 28, as by bolts 29. Properly connected to the valve casing 28 is an intake pipe 30 and an exhaust pipe 31. 70 The valve casing 28 is provided with an outer tapered wall 32 and an inner tapered wall 33 providing a tapered valve space 34 for the tapered annular valve 35. In this particular embodiment the valve 35 is provided with a single port 36 adapted to register with the intake ports 37 and 38 made in the inner and outer walls 33 and 32, respectively, and with a similar exhaust port 37' and 39. A cap 40 is screw threaded to cover 80 the top of the casing 28, as at 41, and is centrally perforated and screw threaded for engagement of a closed tube 42. Adjusting screws 43, pass through the top of the cap 40, and bear upon the top wall 35' of the 85 valve 35. These adjusting screws 43 are intended to prevent the valve 35 from being raised out of the tapered valve space contained between the walls 32 and 33. An additional adjusting means may be provided 90 by the annular shims 44—44 that are contained between the top of the wall 32 and the shoulder 40' of the cap 40. Secured to the valve 35, in a central perforation thereof, or made a part of said valve, is a tube 45 provided with inwardly extending teeth or ribs 46 which are continuous from end to end of said tube. In the present exemplification, tube 45 is made to turn with the valve 35 by means of the feather 47 which engages in the feather-way 48 of the valve, when the two parts occupy their proper relative positions. The lower end of the tube 45 rests in the ring 45' which is secured to the cylinder head 28 by the integral ribs 49—49 leaving spaces 105 50—50 on either side thereof through which the motive fluids and the products of combustion may freely pass to and through the

ports 38 and 39. It will now be seen that when the tube 45 is rotated, the valve 35 is rotated thereby.

Rotatively and centrally fixed to the piston head 20' is a vertically extending tube 51, provided with a shoulder 52 near its lower end within which is a packing ring 53, to bridge the joint between said tube and the upper surface of the piston head 20'. Secured to or made as an integral part of the lower end of the tube 51, is a segmental gear 54. Secured to or constructed as a part of the tube 51, are a series of spaced apart circumferentially extending series of teeth 55, intermediate the ends of said tube, and more clearly shown in Figs. 4 and 8. These teeth are adapted to enter the interdental spaces 56—56 of the tube 45, as shown in Fig. 9. Inside of the tube 51 is another smaller tube 57 which is freely rotatable therein and which projects beyond each end of the larger tube. Secured to or integral with the lower end of the tube 57 is a segment of a gear 58, and to the upper end of the tube 57 is secured a pinion 59, shown in cross section in Fig. 8, having teeth which are also adapted to enter the interdental spaces 56—56 of the valve tube 45 between the teeth 46 that are located within the interior of said tube. The upper end of the rod 57 is reduced and is provided with a screw threaded end 60 and a shoulder 61, against which the pinion 59 is held by a nut 62, that engages the end 60 of the rod 57. A pin 63 may be employed to secure the pinion 59 in place.

The upper end of the pitman or connecting rod 22 carries a geared segment 64 which cooperates with a geared segment 54 that is secured to the lower end of the outer tube 51. The connecting rod is also provided with a geared segment 65 which cooperates with a geared segment 58 that is connected to the inner tube 57. The radial dimensions of the segment 64 bears the same relation to the segment 54 as does the segment 65 with the segment 58 so that the inner and outer tubes 51 and 57 will be oscillated by the oscillatory motion of the connecting rod 22 at approximately the same rate of speed. The tubes 51 and 57 are oscillated by the geared mechanism just described but the rate of speed will be proportional to the cosine of the crank angle or inversely to the sine of the crank angle.

When the crank or wrist pin is passing through a quadrant of its motion, usually indicated as the dead center, or when it is passing from a point taken at one side of a vertical plane through the shaft 17, until it reaches substantially the same point on the opposite side thereof, the tubes 51 and 57 will be rotated at their highest velocities and when the crank pin is passing through the next quadrant of its motion,

that is to say, when it is substantially ascending or descending in its movements to reciprocate the piston, the end connected to the crank pin 17, at this time, is very slightly oscillated and therefore when the pin is passing through this quadrant of its motion the tubes 51 and 57 are practically stationary.

When the crank pin 17 is ascending, as shown in Fig. 1, the tubes 51 and 57, together with the piston 20 are being elevated, or raised, and the teeth 55 of the tube 51 are about to enter the interdental space 56 of the valve tube 45. Just about the time that the teeth 55 on the tube 51 enter said space in the valve tube 45, the pin on 59 leaves engagement therewith, as shown in Fig. 9 of the drawings. By the time the pin 17 begins to pass the dead center point, or through the upper quadrant of its motion, the teeth 55 of the tube 51 have made connection with the valve tube and the segment 64 carried by the connecting rod 22 begins to rotate the segment 54 carried by the tube 51. At the same time the segment 65 rotates the pinion 58 carried by the inner tube 57, in the opposite direction, but inasmuch as the pinion 59, which is connected to the inner tube, is not now connected with the valve, the inner tube 57 is rotated idly. During the movement of the pin 17 through the quadrant of its motion, if the valve 35 has been rotated, through the connections described, so that the port 36 registers with the intake port 38, at the time when the pin 17 is at the end of the upper quadrant of its motion, the valve will now remain open and substantially immovable until the pin 17 has finished the next succeeding quadrant of its motion, or while it is descending. When the pin 17 arrives at approximately the horizontal plane it is shown to be in Fig. 1, but on the opposite side of the shaft 18, the teeth 55 on the sleeve 51 will occupy substantially the disengaged position shown in Fig. 1 and the pinion 59 on the tube 57, will have made engagement with the teeth 46 of the valve tube 45 and now as the crank pin 17 passes through the lower quadrant of its motion, or from the right to the left hand side, the segment 65, which rotates the segment 58 of the tube 57, will be rapidly rotated and move the valve to close the valve port 38, after which the piston 20 will start on its compression stroke. During the next two cycles of the motion of the piston the valve will remain closed, because there are no ports through the casing 28 with which the valve 36 may register during the compression and power stroke of the piston. At the end of the power stroke, however, the valve port 36 will have arrived opposite the exhaust port 39, as shown in Fig. 5, and the next succeeding stroke of the piston will

serve to scavenge the cylinder through the exhaust port and thus the four cycles of the engine have been completed.

I have placed a funnel 68 at the lower end of the tube 57 so that the movement of oil due to the splash of the crank in the casing may cause it to pass up through the interior of the tube 57, and lubricate the valve and connecting parts. Of course, other means may be employed for lubricating these parts, as for instance an oil cup or other similar device may be placed upon the upper end of the closed tube 42. I have perforated the upper wall 35' of the valve 35, as at 69, so as to equalize the pressure on each side of the valve.

While I have shown a single embodiment of my invention for purposes of clear disclosure, it is manifest that changes in the form and disposition of the parts may be made within the scope of the appended claims.

Having described my invention, what I claim is:

1. A valve structure comprising a pair of spaced apart stationary annular ported walls, an annular ported valve member rotatable in the space between said stationary walls and having a perforated base portion extending radially inwardly therefrom, means axially located for rotating said

valve structure and a cap carried by the outer stationary wall extending over the top of the valve structure.

2. The combination with the cylinder of an internal combustion engine, of a valve structure comprising an annular valve member having a base portion extending radially inwardly therefrom and exposed to the pressures within the cylinder, means axially positioned for rotating said valve structure, said base portion having perforations therethrough, and a wall overlying the outer side thereof.

3. The combination with a cylinder, a piston and connecting rod of an internal combustion engine, of a valve structure comprising a removable cylinder head having a chamber communicating with the space within the cylinder, a rotary valve carried by and positioned entirely within said head, and valve operating means extending axially through said head and piston for connection with the connecting rod.

In testimony whereof I hereunto set my hand in the presence of two subscribing witnesses.

EARL E. McCOLLUM.

In the presence of—

MARY F. ALLEN,

STANLEY W. COOK.
